[57] CLAIM

The ornamental design for a pocket display unit, as shown and described.

DESCRIPTION

FIG. 1 is a front side perspective view of a pocket display unit showing my new design;

FIG. 2 is a right side elevation view thereof, it being understood that the left side elevational view is identical thereto;

FIG. 3 is a front side elevational view thereof;

FIG. 4 is a rear side elevational view thereof;

FIG. 5 is a top plan view thereof; and,

FIG. 6 is a bottom plan view thereof.
